ORNAMENTAL KNOB OR HANDLE

Arthur Wiltshire, Jr., Media, Pa.

Application July 13, 1934, Serial No. 734,920

2 Claims. (Cl. 40—8)

My invention has reference to handles or knobs adapted for use with gear shift levers, such as required in automobiles, and for other mechanical devices.

5 My improved handle or knob is of a rounded shape adapted to be easily grasped in the palm of the hand and provided with a monogram or marking device secured in the upper curved surface of the knob and facing in a direction opposite to the shift lever or spindle to which it is secured, the body of the knob or handle being formed of vitreous material such as glass or porcelain, or any other suitable material or composition, and having a shallow recess in which a metallic monogram bearing plate is inset and preferably held in place by friction creating means.

10 My invention is furthermore provided with a screw threaded bushing screwed into engagement with the handle or knob, said bushing being also internally screw threaded whereby it provides rigid engagement between the shift lever or spindle and the handle or knob.

15 My improved handle or knob further consists of the metallic inset plate made to conform to the curved surface of the handle or knob and retained thereon by rearwardly extending prongs forced into engagement with suitably directed holes in the vitreous material so as to bend the prongs sufficiently to make a firm frictional connection 20 between the monogram plate and the vitreous handle or knob.

25 With the above and other objects in view, the nature of which will be more fully understood from the following specification, the invention 30 consists in the novel features of construction hereinafter more fully described and defined in the claims.

35 Referring to the drawing: Fig. 1 is a side elevation of a portion of the shift lever and with my improved knob or handle applied thereto and illustrated in section; Fig. 2 is a front view of my improved handle or knob; Fig. 3 is an inverted perspective view of the monogram plate, showing one form of monogram and a plurality of 40 projecting retaining prongs so positioned and of a shape to engage holes in the vitreous body of the handle or knob; Fig. 4 is an enlarged sectional view of a portion of the handle or knob and illustrating more fully the manner of attaching the monogram plate to the body of the knob; and Fig. 45 50 55 5 is a general view, corresponding to Fig. 1, of a modified form of attachment between the knob and the shift lever.

2 represents the shift lever of an automobile, or any shaft or spindle in a lock or for other pur-

poses. 3 represents a knob or handle portion preferably formed of semi-vitreous material such as porcelain or ductile glass, and may be of one color or formed of varied colors due to admixture of colored glass in the ladle prior to the pressing of the same in suitable molds. The rear portion of the knob body 3 is provided with a recess or blind hole 4 which may be internally screw threaded as at 5 and into which a metal bushing 6 may be screwed for forming a connection between the vitreous knob body 3 and the shift lever 2. It is desirable that the bushing 6 firmly screw into the threaded recess 4 so that when it is fully introduced, the outer thread portions 7 of said bushing will interlock with the threads 5 of the recess 4. After the bushing has been introduced in position upon the knob, the internal threads 8 of said bushing are screwed upon the threaded end 9 of the shift lever 2. In this manner the knob is firmly secured to the shift lever. 5 10 15 20 25 30

As shown in Fig. 1, the face portion of the knob is slightly recessed, as indicated at 10, and into said recess is arranged a monogram plate 11, which plate is made somewhat spherical and preferably so that its outer surface is substantially flush with the outer curved surface of the knob. The plate 11 is preferably made thin and the monogram or ornamentation is provided by cutting or stamping the same through the plate, as indicated at 12, so that through said perforations the color of the vitreous material may be exposed to heighten the effect of the monogram. 30

As considerable rough usage is imparted to the monogram plate in the shifting of the lever, it is important that the union between the said plate 35 and vitreous body of the knob be a firm attachment which will prevent the plate from shifting in a rotatable direction or from pulling off from the surface of the knob. This I accomplish in the following manner: The monogram plate is 40 provided with a plurality of prongs 14a as shown in Fig. 3, which project from the back in an angle toward each other as indicated by the dotted line extensions from the free ends of the said pins 14a, and as also indicated in Figs. 1 and 4. 45 In practice, the front surface of the knob 3 is drilled with a plurality of oblique holes which correspond to the parts marked 13, and which coincide with the oblique prongs 14 of the plate after they are driven into said oblique holes and 50 the monogram plate forced into the recess 10 in the finished article. The prongs 14a when ready to be inserted into the holes 13 are somewhat out of alignment therewith and the points are manually adjusted to insert the ends of the 55

prongs 14a into the exposed open ends of the holes 13, and when they are driven in they assume such position as would coincide with the holes 13 as indicated at 14 in Figs. 1 and 4.

- 5 When the monogram plate 11 is thus secured in position upon the knob, it will be free from all projections, such as would occur if screws were employed. In practice, it is found that the friction between the pins 14a and the holes 13 is 10 10 amply sufficient to positively retain the plate against displacement by any ordinary manipulation of the shift lever in the operation of the automobile, or for any other practical use of the improvements.
- 15 Referring to Fig. 5, the general construction may be considered as corresponding to that shown in Fig. 1, with the single exception that the bushing 6 of the knob is locked in definite position on the end of the shift lever 2 by means 20 of a lock nut 15. This construction enables the knob to be set, with the monogram plate, in proper position and thereafter locked in such desired position. Any other suitable means for locking the knob upon the shift lever may be 25 employed if so desired.

In cases where the knob is to be applied to shift levers of different diameters and threads, it is only necessary to cut the inner screw threads 8 of the bushing in the shape and dimension to 30 correspond to the threaded end 9 of the shift lever 2.

Of course the ornamental knob or handle illustrated and described herein may be modified in various ways without departing from the invention herein set forth and hereafter claimed.

5 I claim:

1. A knob for gear shift levers and the like, comprising a knob portion of vitreous material slightly countersunk on its exposed face, a monogram plate fitting flush into the countersunk portion to provide a smooth upper face in the 10 knob, said knob having holes extending at an angle to the surface thereof, said plate having prongs slightly resilient and normally extending at right angles to the under surface of the plate, and said plate being attached to said knob by 15 means of said prongs extending into said holes.

2. A knob for gear shift levers and the like, comprising a knob portion of vitreous material slightly countersunk on its exposed face, a monogram plate fitting flush into the countersunk portion to provide a smooth upper face in the knob, said knob having holes extending at an angle to the surface thereof, said plate having prongs slightly resilient and normally extending at right angles to the under surface of the plate, 20 and said plate being attached to said knob by means of said prongs extending into said holes, said prongs when in the holes being bent whereby they are frictionally held therein.

25
